UNITED STATES PATENT OFFICE.

JOSEPH FEDERICO, OF NEWARK, NEW JERSEY.

COMBINATION BRUSH AND SPRAY DEVICE.

Application filed February 10, 1928. Serial No. 253,450.

The present invention relates to an improved combination brush and sprayer, and the primary object of the invention is to provide a device of this character which is 5 of extremely light and simple construction and which brush is primarily intended for use in shampooing the hair and general bathing purposes.

A further object of the invention is to 10 provide a combination brush and sprayer embodying an arrangement whereby the sprayer is readily detachable from the brush for allowing independent use of either the sprayer or the brush.

15 A still further object of the invention is to provide a combination brush and sprayer of such construction as to allow for use of the device in the manner of an ordinary brush without liability of injuring one's 20 body thru any projecting portions of the device.

25 A still further object of the invention is to provide a simple construction for combination brush and sprayer devices whereby the sprayer is effectively held against displacement when coupled to the brush.

30 Other objects and advantages of the invention will be apparent during the course of the following detailed description, taken in connection with the accompanying drawing, forming a part of this specification and in which drawing:

35 Figure 1 is a central longitudinal section thru the improved combination brush and sprayer.

Figure 2 is a top plan view of the assembled device.

Figure 3 is a bottom plan view of the device.

40 Figure 4 is a plan view looking at the outer end of the sprayer.

45 Referring to the drawing in detail and wherein similar reference characters designate corresponding parts thruout the several views, the letter A designates the brush portion of the device and the letter B the sprayer for detachable connection with the brush A.

50 The brush A embodies a back 5 which has been shown as being of substantially oval shape in plan, and projecting from the in-

ner face of the back 5 are suitably arranged tufts of bristles 6. Provided thru the central portion of the back 5 is a circular shaped opening 7 which as will be observed 55 tapers from the outer face 8 of the brush back to the inner face 9. As will be observed in Figure 3 the tufts of bristles 6 are arranged in circular formation about the peripheral edge of the opening 7 and thus form 60 an opening thru the bristles for allowing free passage of the water or other liquids being sprayed. By observing Figure 3 it will also be seen that the tufts of bristles 6 are arranged in rows which extend radially 65 of the axis of the opening 7 and thus provide a series of radially extending channels 6' between the rows of bristles, and certain of which channels as will be observed provide unobstructed passageways from the 70 opening to the periphery of the brush back. These open channels 6' will allow the water to freely and quickly pass between the bristles so that the water passing thru the apertures in the plate 12 will not be obstructed by any appreciable accumulation of 75 water retained in the pocket formed by the encircling tufts of bristles. By so having the brush back of oval shape it will be seen that the channels at the sides of the brush 80 will be relatively short and thus allow for free escape of the water being discharged thru the apertured portion of the sprayer B.

Referring now to the sprayer B for detachable connection with the brush A, the 85 same is preferably formed from sheet metal and is of two part construction embodying a cap portion 10 and a hollow head portion 11. The cap portion 10 is of frusto-conical shape and of a depth substantially equal to 90 the thickness of the brush back 5. The taper of the frusto-conical shaped cap portion 10 corresponds to the taper of the opening 7 and is provided with a flat perforated base plate 12 which when the cap is inserted 95 in the tapering opening 7 has its outer face extending flush with the inner face 9 of the brush back as clearly illustrated in Figure 1. Thus it will be seen that the corresponding taper of the opening 7 and cap portion 100 10 serve to limit movement of the cap portion thru the opening in the brush back.

The head portion 11 is of substantially bell shape providing a hollow tubular neck 14 below which the head portion flares to a diameter substantially equal to the internal 5 diameter of the larger end of the tapering cap portion 10. Projecting radially from the lower end of the head portion 11 and at diametrically opposite points, is a pair of flat ears 15 which are intended to project in- 10 to shallow pockets 16 provided in the outer face of the brush back at diametrically opposite points about the opening 7. As will be observed in Figure 2, these shallow pockets 16 are of a width greater than the width 15 of the ears 15. Each of the ears 15 is provided with a circular opening 17 having a restricted lateral way 18, and as will be observed in Figure 4, these lateral ways 18 extend in opposite directions from the openings 17 circumferentially of the sprayer.

The outer edge of the cap portion 10 is intended to be spun over the enlarged lower end of the head portion 11 to form a sealed joint between the portions 10 and 11. This 25 connection of the portions 10 and 11 as by the spun bead 19 forms a closed chamber for the sprayer whereby water entering the sprayer thru the neck 14 will be discharged in a spray thru the apertures provided in 30 the flat base plate 12. The neck 14 serves as a means for connecting a flexible hose of any suitable nature to the sprayer.

Carried by the brush back 5 and arranged one within each of the shallow pockets 16, 35 are headed coupling members 20 the rounded heads of which are of a diameter slightly less than the diameter of the openings 17 in the ears 15 and the shank portions of which are of a diameter substantially equal to the 40 width of the lateral ways 18. These coupling members 20 may either be in the form of round headed screws or short nails, and are arranged so that the head portions are spaced above the base of the pockets 16 for 45 a distance substantially equal to the thickness of the ears 15. As will be observed in Figure 1, the pockets 16 are of a depth substantially equal to the thickness of the ears 15 so that the outer surfaces of the ears 50 when arranged in the pockets extend flush with the outer face 8 of the brush back.

In attaching the sprayer to the brush back, the frusto-conical cap portion is inserted into the tapering opening 7 and the 55 ears 15 arranged so that the head of the coupling members 20 will project thru the openings 17. The brush may then be slightly rotated for causing the shank of the coupling members to move into the re- 60 stricted lateral ways 18 and whereupon the sprayer will be coupled to the brush. Thus it will be seen that thru slight relative ro- 65 tary movement of the brush and sprayer that the sprayer may be coupled or disconnected from the brush for allowing inde-

pendent use of either the sprayer or the brush.

It will be apparent by observing the drawing that no undesirable projection is provided which would be objectionable and 70 may possibly result in injury to one's body thru use of the combination brush and spray device. It will be seen that the only projections whatsoever are the rounded head 75 portions of the coupling members 20 and the spun bead 19, and neither of which form an objectionable projection.

From the foregoing description it will be apparent that a novel construction for a combination brush and spray device has been 80 provided wherein a tapered portion of the sprayer is received in a correspondingly shaped opening provided in the brush back, and which sprayer is provided with sub- 85 stantially flat ears whereby the sprayer may be detachably coupled to the brush in a simple and efficient manner and without providing any objectionable projections. It will also be apparent that by so having the cap portion 10 of a depth substantially equal to 90 the thickness of the brush back 5 that the perforated base plate 12 does not project pass the inner face of the brush back and that the lower flaring end of the head portion 11 merges into the outer face 8 of the 95 brush back so that no objectionable protuberances will be formed thru the two part construction of the sprayer.

Changes in detail may be made to the specific form of the invention herein shown 100 and described, without departing from the spirit of the invention or the scope of the following claims.

I claim:

1. A device of the class described comprising- 105 a brush embodying a back having a tapering opening extending therethru and bristles extending from the inner face of the brush back about the smaller end of the opening, a chambered member embodying 110 a tapering cap portion fitting in said opening between the faces of the brush back and having a flat perforated base plate at its smaller end, and means for detachably connecting the chambered member to the brush back. 115

2. A device of the class described comprising a brush embodying a back having a tapering opening therethru and bristles extending from the inner face of the back about the smaller end of the opening, a 120 sprayer including a shallow frusto-conical shaped cap portion fitting in said tapering opening and provided with a perforated base portion, and a head portion provided with laterally projecting ears, and means for detachably connecting the sprayer member by said ears to the brush back. 125

3. A device of the class described comprising a brush embodying a back having an opening therethru and provided at its outer 130

face with shallow pockets extending into the opening, a sprayer member including a perforated portion fitting in said opening and a head portion having a flaring lower end and flat wings projecting from the lower flaring end of the head portion and extending into said pockets, said ears each being

provided with an opening having a restricted lateral way, and headed coupling members carried by the brush back and arranged with- 10 in the pockets for detachable engagement by said ears.

JOSEPH FEDERICO.
